PHASING TOOL

William V. Carney, Brooklyn, and Paul V. De Luca, Port Washington, N.Y., assignors to Markite Corporation, New York, N.Y.

Filed Dec. 28, 1965, Ser. No. 516,983
2 Claims. (Cl. 81—90)

This invention relates to phasing tools for servo mounted components in general and more particularly to means for phasing a servo component after it has been placed in the system.

A problem has existed in the phasing of servo mounted components. Servo mounting is a particular type of installation wherein the instrument housing is placed in an aperture in the panel. Fastening means such as screws threadably engaged in the panel cooperate with members arranged to fit in an annular groove in the instrument housing. A servo mounting is differentiated from another common type wherein the mounting screws pass through clearance holes in the panel and are threadably engaged in the instrument housing. It has often been found necessary after installation to phase a gang of conventional potentiometers with respect to a shaft in the mechanical system. Since the technician was unable to otherwise get at the potentiometer case, prior to the present invention, it was the practice to loosen the mounting dogs slightly and then hit the rear cover of the potentiometer with a hammer and screwdriver. Because of this mishandling, the individual potentiometers in the gang were often moved out of phase with each other.

The present invention provides a very simple, low cost, yet effective solution to this problem. For illustrative purposes only, potentiometers will be described but it should be clearly understood that the invention is not limited thereto. The invention may, in fact, be practiced with any servo mounted component that requires phasing after it is placed in the system.

In one of the embodiments illustrated, a gear tooth form or knurl is formed on the front cover or housing of the potentiometer. A hollow pinion is placed over one of the screw heads holding the mounting dogs in place, the pinion being arranged to mesh with the housing gear such that the potentiometer housing is angularly displaced when the pinion is manually rotated. Since the gear on the potentiometer housing is located on the front cover, the external phasing procedure does not disrupt the cup-to-cup phasing relationship of a multigang potentiometer.

In another embodiment a hole in the panel is utilized to receive a pin having a coaxial gear and handle. In this instance the dogs are loosened but are not used for piloting. The pin on the tool serves this function to permit the coaxial gear to mesh with a gear formed on the instrument housing. Rotation of the tool handle causes rotation of the meshing gears and phasing of the instrument.

Accordingly, it is an object of this invention to provide improved low cost phasing means for a servo mounted component.

Another object is to provide an improved servo housing having phasing means integral therewith.

An additional object is to provide a simple phasing tool that will cooperate with the aforementioned housing.

A particular object is to provide an improved servo housing having integral phasing means that may be frictionally rotated by means of a mating phasing tool.

Still another object is to provide a phasing tool for the aforementioned housing that cooperates with the mounting means of the servo component.

These and other features, objects and advantages of the invention will, in part, be pointed out with particularity and will, in part, become obvious from the following more

2

detailed description of the invention taken in conjunction with the accompanying drawing which forms an integral part thereof.

In the various figures of the drawing, like reference characters designate like parts.

In the drawing:

FIG. 1 is an exploded, perspective view of a typical servo component together with the phasing means of the present invention;

FIG. 2 is an elevational view illustrating the servo component of FIG. 1 secured to a mounting panel;

FIG. 3 is an enlarged, fragmentary elevational view showing the phasing tool in operation;

FIG. 4 illustrates in elevation an alternative embodiment of the present invention; and

FIG. 5 is a side elevational view, partly in section, of another alternative embodiment.

Referring now to FIG. 1 of the drawing, servo component 10 is a multi-unit ganged potentiometer having a shaft 12 coaxially disposed in housing 14. Cylinders 16 together with a rear cover 18 and a front cover 20 comprise a unitary housing. Terminals 22 integrally mounted on each cylindrical housing portion 16 are electrically connected to internal, conventional potentiometer elements and are adapted to be connected to an external utilization device.

Front cover 20 is provided with a first piloting diameter 24 which is disposed in an appropriately sized aperture 26 in mounting panel 28. An annular groove 30 formed in the front cover receives clamping dogs 32 that secure the potentiometer to the panel by means of screws 34. Just rearward of groove 30 there is formed a gear tooth form 36. It should be noted that while a fairly accurate gear tooth has been illustrated, it is not absolutely essential. A knurl, shown as 36a in FIG. 4, will produce sufficiently deep and evenly spaced ridges to be a reliable substitute for the gear teeth. It should also be appreciated that either the gear or knurl need not be continuous. A small segment of either in the area of a clamping dog is all that is required since rotation of the instrument housing for phasing purposes is not usually too extensive.

Phasing tool 40 is comprised of a hollow member 42 having gear teeth 44 formed at one end 46. A knurled surface 44a (FIG. 4) may be substituted for the gear form. To utilize the phasing tool, screws 34 are first slightly loosened and then tool end 46 is piloted on one of the screw heads so that gears 36 and 44 are in mesh. Rotation of the tool about the screw axis causes rotation of the potentiometer housing about its central shaft. However, the cup-to-cup relationship in a ganged potentiometer is not disturbed because the internal potentiometer components are secured to their respective cases; the cases and end covers are an integral unit and it is the front end cover that is rotated by the phasing tool.

The force required to phase the potentiometer is derived from the coefficients of friction between the material of the front cover and the mating diameter of the mounting panel. To minimize the force required, it is contemplated that a low coefficient of friction plating material be utilized on the potentiometer case. Teflon-impregnated anodizing on aluminum is an example of a suitable material.

The phasing tool has been shown to be cylindrical so that a simple screwdriver 48 can fit therethrough. This serves to support the phasing tool while it is being rotated and in addition permits tightening down on the screw after phasing is accomplished without having to remove the tool. It should be evident, however, that the phasing tool may have a solid body portion with only a cup-shaped end about which is formed the pinion. The cup need only be deep enough to freely accommodate the screw head.

An alternative embodiment of the invention is illustrated in FIG. 5. An instrument 50, of the type requiring phasing, is mounted in panel 52 by means of clamping dogs 54. Only one clamp is shown, the other being on the opposite side of the instrument 180° away. The clamping arrangement is, of course, but one of several that may be employed. However, in contrast to the previous embodiments the mounting screws herein are not utilized for piloting the phasing tool. Gear 56 is formed on the front cover of the instrument housing proximate the mounting panel.

Phasing tool 58 is comprised of an elongated handle 60 and a gear 62 at one end thereof. Extending coaxially from the face of the gear is a piloting pin 64. As shown in the drawing, pin 64 is adapted to be received in an aperture 66 in the panel. The aperture is located close to the instrument so that when the tool is inserted gears 56 and 62 will mesh. If the clamping dogs are first loosened, then rotation of the tool will phase the instrument. As noted in the previous embodiments, the mating surfaces both driving and driven need not be completely circular. As a matter of fact, only a single notch on the instrument periphery and a single tooth on the tool will provide sufficient angular movement of the instrument for most applications. It is also practical, and may even be desirable from an appearance point of view, to form aperture 66 as a recess that does not go completely through the panel but which is deep enough to receive pin 64.

There has been disclosed heretofore the best embodiment of the invention presently contemplated and it is to be understood that various changes and modifications may be made by those skilled in the art without departing from the spirit of the invention.

What is claimed is:

1. The combination, with a servo mounted instrument having a housing releasably secured to a panel by means

of clamps and screws and a shaft disposed in the housing to define a longitudinal axis, of:

- (a) a driven surface formed on the outside of the instrument housing;
- (b) an elongated, rotatable tool having a longitudinal axis, said tool, in operation, being rotatable about an axis parallel to the housing axis;
- (c) a coaxial driving surface formed integrally at one end of said tool; and
- (d) coaxial piloting means formed integrally with said driving surface, wherein said piloting means is an opening in the end of said tool proximate said driving surface, said opening being at least as large as the diameter of the head of one of said screws, said driving and driven surfaces being in meshing engagement when the opening of said tool is disposed about the screw head.

2. The apparatus in accordance with claim 1 wherein said opening extends through the entire length of said tool to form a passageway, whereby a screwdriver may be inserted within said passageway to engage said screw-head.
